UNITED STATES PATENT OFFICE.

DAVID HALL, OF WILKINSBURG, PENNSYLVANIA, ASSIGNOR TO WESTINGHOUSE ELECTRIC & MANUFACTURING COMPANY, A CORPORATION OF PENNSYLVANIA.

FIELD-MAGNET POLE PIECE FOR DYNAMO-ELECTRIC MACHINES.

Application filed February 4, 1918. Serial No. 215,373.

To all whom it may concern:

Be it known that I, DAVID HALL, a citizen of the United States, and a resident of Wilkinsburg, in the county of Allegheny and

5 State of Pennsylvania, have invented a new and useful Improvement in Field-Magnet Pole Pieces for Dynamo-Electric Machines, of which the following is a specification.

My invention relates to dynamo-electric 10 machines and it has special relation to the structure of field magnet pole pieces employed therein.

The object of my invention is to provide 15 a field magnet pole piece of such character that, when used in a generator, it will insure effective voltage regulation and, when used on a motor, will insure good speed regulation over a wide range of operating conditions.

20 Heretofore, it has been customary to provide direct-current generators with field-magnet pole pieces having notches therein by means of which good voltage regulation was effected over a relatively limited range.

25 By my invention, this range is extended to cover the entire voltage range of the machine. A pole piece constructed in accordance with my invention is provided with non-magnetic portions intersecting the flux 30 path, the length and cross-section of the non-magnetic material both being adjustable.

Referring to the drawing, Fig. 1 is a 35 transverse sectional view of a portion of a dynamo-electric machine embodying my invention; Fig. 2 is a diagram showing the flux values, for various values of field current, of a pole piece embodying my invention, as compared with corresponding values 40 for a solid pole piece.

Referring more particularly to Fig. 1, I have shown a field frame 1 to which a pole piece 2 constructed in accordance with my invention, is attached by means of a bolt 3. 45 The pole piece 2 is spaced from the field frame 1 by two interposed spacing members 4 and 5 of metal each of which is composed of an outside rim 6 of magnetizable material, preferably iron, and a center portion 7 of

some non-magnetizable material, such, for 50 example, as brass. Thus paths are provided for the magnetic lines of force from the field frame 1, through the magnetizable rims 6 of the spacing members 4 and 5, to the pole piece 2. Slots 8 and 9 are cut into the pole 55 piece at the junctions of the iron and brass portions of the spacing members 4 and 5 to form fingers 10 and 11 which are parts of the magnetic circuit.

When the current in the field-magnet 60 coil (not shown) is small, substantially the entire field flux is through the iron rims 4 and 5 and the fingers 10, on account of the low reluctance of these paths, but, when the current becomes stronger, the flux passes 65 through the brass portion of the spacing member 5 to the fingers 11. When the current is very strong, the entire pole piece is energized. When the field flux is passing 70 through the fingers 10 and the current increases, the fingers begin to approach saturation, causing the saturation curve, shown at A in Fig. 2, to bend away from a solid-pole-piece saturation curve shown at B. However, the curve does not continue to bend 75 over indefinitely because prevented by the leakage flux across the brass portion of the spacing member 5 to the fingers 11. Since flux leakage across the brass portion of the liner 5 occurs gradually, the magnetization 80 curve A does not become horizontal but continues upwardly, though at a smaller angle of inclination, thus gradually approaching the solid-pole-piece curve B. As the fingers 11 approach saturation, the same action occurs, so that, although the curve reaches 85 practically the same value, at high current, as with the solid pole piece, it has a better voltage regulation for all values of current;

that is to say, there is a definite value of 90 field flux and output voltage for each value of field-exciting current over an exceedingly wide range, as is desirable, for example, in exciter machines.

Also, by substitution of spacing members 95 of magnetizable and non-magnetizable material and of the proper proportions, any desirable shape of curve may be secured.

While the preceding description of operating characteristics relates to generators, it is, of course, obvious that a similar structure would provide good speed regulation when used in a motor.

While I have shown one form of my invention and described, in detail, one application of the same, it will be obvious to those skilled in the art that it is susceptible of various minor changes and modifications without departing from the spirit thereof, and I desire, therefore, that only such limitations shall be placed thereupon as are imposed by the prior art or are specifically set forth in the appended claims.

I claim as my invention:

1. In a dynamo-electric machine, a field frame, a field-magnet pole piece mounted on said frame, and a spacing member disposed intermediate said pole piece and said frame and comprising a central portion composed of non-magnetic material and a rim portion composed of magnetic material.

2. In a dynamo-electric machine, a field frame, a field-magnet pole piece mounted on said frame, and a plurality of spacing members disposed intermediate said pole piece and said frame in stacked relation, said spacing members each comprising a central portion composed of non-magnetic material and a rim-portion composed of magnetic material, said spacing members being so arranged as to provide magnetic paths of relatively high reluctance at the center of the pole pieces and of successively lower reluctance nearer the sides of the pole pieces.

3. In a dynamo-electric machine, a field frame, a field-magnet pole piece mounted on said frame and provided with radial slots adjacent the base thereof, and a spacing member disposed intermediate said field frame and said field-magnet pole piece and comprising portions of magnetizable and of non-magnetizable material disposed in side-by-side relation, the junction of the magnetic and non-magnetic portions of the said spacing member being disposed opposite the slots in said pole piece.

4. A dynamo-electric machine frame having a field-magnet pole piece, certain base portions of which are cut away, and spacing members composed of magnetizable and non-magnetizable portions inserted between the frame and said pole piece and bridging the spaces formed by cutting away said base portions to provide paths for the magnetic flux of relatively high reluctance at the center of said pole piece and paths of successively lower reluctance nearer the sides of said pole piece.

5. A spacing member having an outer portion of magnetic material and a central portion of non-magnetic material disposed in the same plane.

6. A composite spacing member having

an outer rim portion of magnetic material and an inner portion of non-magnetic material and adapted to be disposed in a flux path to regulate the reluctance thereof.

7. A composite spacing member adapted 70 to be disposed in the path of magnetic flux to regulate the density thereof, comprising a plurality of superposed members of magnetizable and non-magnetizable material, the respective materials of each of said members 75 being disposed in the same plane and having the joints therebetween disposed in staggered relation with respect to the joints of the adjacent members.

8. A composite spacing member adapted 80 to be disposed in the path of magnetic flux to regulate the density thereof, comprising a plurality of superposed members of magnetizable and non-magnetizable material, the respective materials of each of said members 85 being so disposed in the same plane that the magnetizable portion of one of said members overlaps the non-magnetizable portion of an adjacent member.

9. In a dynamo-electric machine, a field frame, a field-magnet pole piece mounted on said frame, and a spacing member disposed intermediate said pole piece and said frame and comprising an annular rim portion composed of magnetic material.

10. In a dynamo-electric machine, a field frame, a field-magnet pole piece mounted on said frame, and a plurality of spacing members disposed intermediate said pole piece and said frame in stacked relation, said spacing members each comprising an annular rim portion composed of magnetic material, said spacing members being so arranged as to provide magnetic paths of relatively high reluctance at the center of the pole pieces and of successively lower reluctance nearer the sides of the pole pieces.

11. In a dynamo-electric machine, a field frame, a field-magnet pole piece mounted on said frame and provided with one or more radial slots adjacent the base thereof, and means disposed intermediate said field frame and said field-magnet pole piece and comprising one or more spacing portions of solid magnetizable material and one or more portions of non-magnetizable material disposed in side-by-side relation, the junction of the magnetic and non-magnetic portions of the said means being disposed opposite the slots in said pole piece.

12. A dynamo-electric machine frame having a field-magnet pole piece, said pole piece being slotted to provide a plurality of fingers certain portions of which are cut away at points remote from the air gap of the machine to provide a path or paths for the magnetic flux of relatively low reluctance through certain of said fingers and a path or paths of higher reluctance through other of said fingers.

13. A composite spacing member adapted to be disposed in the path of magnetic flux to regulate the density thereof, comprising a plurality of superposed magnetizable spacing members of different diameters. ¹⁰

14. A composite spacing member adapted to be disposed in the path of magnetic flux

to regulate the density thereof, comprising a plurality of superposed annular magnetizable members of different inner diameters.

In testimony whereof, I have hereunto subscribed my name this 30th day of Jan. 1918.

DAVID HALL.
